GRILLE BAR FOR AN AUTOMOBILE

Frederick Reynolds, Detroit, Mich., assignor to Chrysler Corporation, Highland Park, Mich., a corporation of Delaware

Application March 18, 1950, Serial No. 8,625

Term of patent 7 years

(Cl. D14—18)

To all whom it may concern:

Be it known that I, Frederick Reynolds, a citizen of the United States, residing in the city of Detroit, county of Wayne, and State of Michigan, have invented a new, original, and ornamental Design for a Grille Bar for an Automobile, of which the following is a specification, reference being had to the accompanying drawing, forming part thereof, in which:

Fig. 1 is a front elevational view of a grille bar for an automobile showing my new design;

Fig. 2 is a top plan view thereof;

Figs. 3 and 4 are cross sectional views taken on the lines 3—3 and 4—4, respectively, of Fig. 1; and

Fig. 5 is a front elevational view of the grille bar for an automobile of my invention, the broken lines showing therein of a portion of the automobile being for illustrative purposes only.

I claim:

The ornamental design for a grille bar for an automobile, substantially as shown and described.

FREDERICK REYNOLDS.
